UNITED STATES PATENT OFFICE

2,623,090

ELECTRON DISCHARGE DEVICE OF THE
DISK SEAL TYPE

Paul G. Bohlke, Roslyn Heights, and Francis C. Breeden, Flushing, N. Y., assignors to Sylvania Electric Products Inc., a corporation of Massachusetts

Application December 19, 1947, Serial No. 792,786.

6 Claims. (Cl. 174—50.52)

1

This invention relates to an electron tube and to contact structure having particular application to tubes of the disc-seal type.

In special types of electron devices, such as the cavity resonator types, disc-seal tubes are used extensively and generally form a part of the main assembly thereof. The operation of mounting a disc-seal tube within a cavity resonator has been a delicate as well as complicated operation, entailing, generally, the disassembly of the cavity unit to remove the tube, and reassembly of the cavity unit after insertion of the disc-seal type tube. The nature of the contacts for connecting the disc-seal type tube to the cavity-resonator circuit is responsible for this tedious, delicate and complicated operation. Special tools are required to assemble and disassemble the cavity resonator unit. Valuable time is thus lost when it becomes necessary to change tubes within the unit for repair or replacement purposes.

In addition to the above the old type of electrode contactor is fragile, susceptible to distortion and fracture with use, and thus makes new tube replacement requirements frequent.

It is, therefore, an object of our invention to provide an electron tube of the disc-seal type with an improved external structural arrangement which facilitates the mounting and demounting of the tube in the surrounding associated equipment.

Another object of the invention is to provide a disc-seal type tube which eliminates the use of special tools when a disc-seal type tube is to be mounted in a cavity resonator unit or the like.

A further object of the invention is to provide a novel disc-seal tube electrode contact structure to permit the "plug-in" insertion of the said type tube within a cavity resonator.

Another object of the invention is to provide a positioning means for facilitating the entry of said disc-seal type tube into a portion of said cavity resonator having means for electrically contacting terminals of electrodes within said tube, and eliminating possibility of damage to said means.

A further object of the invention is to provide a stop associated with said tube structure which coacts with a portion of the cavity resonator unit to determine insertion depth of the tube within the cavity resonator unit.

Further objects and advantages of our invention will become apparent from the following description referring to the accompanying drawing and the features of novelty of our invention

2

will be pointed out in the claims annexed to and forming part of this specification.

In the drawing:

- Fig. 1 is an elevation of an electron tube and a cavity resonator.
Fig. 2 is an elevation, partly in section, of an electron tube located in a cavity resonator.
Fig. 3 is an enlarged elevation, partly in sections, of an electron tube.

10. Fig. 4 is an enlarged fragmentary view of the tube stop and a contact member.
Fig. 5 is an enlarged fragmentary view of the tube stop, a contact member, and a modified guide surface.

15. In the drawings, only sufficient structure of the electron device is shown as is required to illustrate the invention.

- Referring in detail to the drawings, number 1 of Fig. 3 designates a possible tube structure embodying the invention herein. The tube structure 1 comprises an envelope 2 having a plurality of sections such as 3, 4 and 5; a cylindrical base 6 having an extended member 7 at one end thereof, and pin connectors 8 for the purpose of providing external electrical means for electrodes (not shown) interior the tube envelope 2; a cap 9 for the purpose of providing external electrical connection means for another electrode (not shown) interior the tube envelope 2; and radial connectors 10 and 11 for the purpose of providing electrical connection means for other electrodes (not shown) interior the tube envelope 2.

- It is to be noted that section 3 and 4 of envelope 2 are separated by a disc 12 which forms a part of electrode connector 10. In more detail, electrode connector 10 is formed by causing disc 12 to be spun over a metal ring 13 having a first portion, 13a, of substantially uniform diameter, and having a chamfered edge 14 or a second portion of diminishing diameter, and a shoulder 15. The disc 12 is spun over said ring 13 in a manner to retain the shoulder 15 in a plane perpendicular to the longitudinal axis of the tube structure 1, and provide a guide and contact surface 14a of diminishing diameter, and a contact surface 10a of uniform diameter.

- Sections 4 and 5 of the envelope 2 are likewise separated by a disc 16 which forms a part of electrode connector 11. In more detail, electrode connector 11 is formed by causing disc 16 to be spun over another metal ring 17, having a diameter equal to or in excess of the diameter of ring 13, so as to form a connector equal to

or larger in diameter than the diameter of connector 11.

The construction of an electron tube in this manner is particularly beneficial for the reasons that, the electrode connectors 10 and 11 achieve mechanical strength; the choice of diameters for said electrode connectors permits the mounting of the tube structure 1 in a manner wherein both connectors are engaged with cavity resonator contacts in one operation; the depth to which the tube is inserted into a cavity is controlled by means of the shoulder 15 coming into contact with a stop within the cavity resonator assembly; and the cavity resonator may be constructed to have the contact means therein form a path for electrical currents at the electrode plane if desired.

The utility and novelty of the invention may be more fully appreciated by reference to Figs. 1 and 2. With reference to Figs. 1 and 2, cavity resonator 18 comprises cylinders 19 and 20 having contact members 21 and 22 respectively. For the purpose of illustration, the inside radius of contactor 21 has been chosen as smaller than the inside radius of contactor 22. When the tube is inserted in the cavity resonator it is seen that mounting is facilitated in that if the average longitudinal axis of the tube structure is not perpendicular to the transverse plane of contactors 21, the contactor would nevertheless ride on chamfered edge 14a, and down to the electrode contactor surface 10a of disc 12, thus not bending or otherwise injuring the contactor member 21 or electrode connector 10. The average longitudinal axis of the tube structure is brought into alignment with the cavity resonator when the tube electrode connector 11 is inserted in cavity connector 22, causing shoulder 15 to abut the inside cylinder stop 23 and determine the distance to which the tube structure 1 may be inserted within the cavity 18. Tubes removed and reinserted are thus always inserted to the same depth.

In adapting the invention to tube contact structures, various structural features may become a matter of choice within the scope of the invention disclosed. For example, the shoulder and chamfered edge may be modified as shown in Fig. 5 wherein corresponding parts are identically numbered. The tube contact members may be formed of any suitable material and the reinforcing ring may be eliminated. Therefore, although we have shown and described a particular embodiment of our invention, we do not desire to be limited to the embodiment set forth. It is our intention to cover all modifications as may come within the scope of the appended claims.

We claim:

1. An electron tube including an envelope, a metal ring surrounding said envelope, said ring having a chamfered edge, and an annular terminal sealed through said envelope and lying against the edge of said ring remote from the chamfered edge of said ring and lying over the outer surface of said ring including said chamfered edge.

2. An electron tube including an envelope, a first metal ring surrounding said envelope, a first annular terminal sealed through said envelope and lying over the outer surface of said first ring, a second metal ring of smaller diameter than said first ring and having a first portion of substantially uniform diameter and

a second portion of diminishing diameter terminating in an end abutment on the side thereof remote the first ring, and a second annular terminal sealed through said envelope and lying over the outer surface of said uniform diameter portion and diminishing diameter portion of said second ring.

3. An electron tube including an envelope, a first metal ring surrounding said envelope, an 10 annular terminal sealed through said envelope and lying over the outer surface of said first ring, a second ring of smaller diameter surrounding said envelope, said second ring having a chamfered edge, a second annular terminal sealed through said envelope at the side of said ring remote the chamfered edge of said ring, said second annular terminal overlying the outer surface of said second ring.

4. An electron tube including an envelope, an 20 electrode terminal at a longitudinal extremity of said envelope, a metal ring having a first portion of a fixed outer diameter and a second portion of diminishing diameter in a direction facing said electrode terminal and mounted in 25 a plane with said diameters perpendicular to the longitudinal axis of said envelope and an annular electrode sealed through said envelope and formed over the outer surface of said ring.

5. An electron tube including an envelope, a 30 plurality of electrode connecting terminals at the longitudinal extremities of said envelope, a first metal ring surrounding said envelope, and positioned in a plane perpendicular to the longitudinal axis of said envelope, a first annular 35 terminal sealed through said envelope and formed over the outer surface of said first ring, a second metal ring of smaller diameter than said first ring and having a portion of its outer diameter diminishing on the side remote said first ring and positioned in a plane perpendicular to the longitudinal axis of said envelope, a second annular terminal sealed through said envelope and formed to lie over the outer surface of said second ring.

6. An electron tube comprising an envelope, a first metal ring surrounding a portion of said envelope, a first annular terminal sealed through said envelope and formed to lie over the outer surface of said first ring, a second 50 metal ring of smaller diameter than said first ring surrounding another portion of said envelope and an annular terminal sealed through said envelope and formed to lie over the outer surface of said second ring in a direction opposite to said first beaded over annular terminal.
